[57] ABSTRACT

An entirely automatic apparatus for fabricating loose-leaf binders includes a first station for receiving the binder cover and for punching holes in the cover. The cover is then transported to a second station where it is automatically combined with spine members which are fastened to the cover. Then, the cover passes to a third station where a metal is positioned against the spine of the binder. Thence, the binder passes through a fourth station which fastens the metal to the spine members.

APPARATUS FOR MANUFACTURE OF LOOSE-LEAF BINDER

BACKGROUND OF THE INVENTION

This invention relates to an apparatus for the construction of a loose-leaf binder. Generally, binders can be classified into three categories. (1) A cut-flush or one-piece binder is comprised of a single case or outside cover cooperable with a metal utilized to hold inner loose-leaf sheets. (2) A vinyl binder of the concealed or exposed rivet type includes a case fabricated from a pair of outer sheets, usually vinyl. The sheets are heat sealed together about a center board and a metal is then attached by means of rivets to the case or cover fabricated from the vinyl sheets. (3) The turned-edge or three-piece binder of the concealed or exposed rivet type includes a pair of fiberboards glued to a cover. The edges of the cover are then turned over the fiberboard and a liner or lining is secured to the opposite sides of the fiberboard. A metal is then attached by means of rivets or the like to the center of the cover fabricated from the fiberboards.

Thus, in general, the binder includes a case, which is the outside covering portion of the binder, and a metal, which is attached to the case by some means and is utilized to hold the sheets of paper or material in the binder. There are numerous types of metals such as prong, ring and post metals as will be recognized by those skilled in the art.

The binders as described above are typically manufactured by manual operation or by a semi-automatic operation requiring a great amount of manual labor. In the example of the invention which will follow, the turned-edge of three-piece type of binder is discussed in detail. A typical apparatus utilized to make a specific embodiment of a turned-edge or three-piece binder is disclosed in the prior art patent to Hildmann, U.S. Pat. No. 2,718,018. The apparatus disclosed in the Hildmann patent as well as the binder which the apparatus manufactures is an excellent product and many millions of binders of this type have been made and utilized.

However, in U.S. Pat. No. 3,175,847, there is disclosed an improved binder construction which has great utility for loose-leaf publications. While the binder shown in the No. 3,175,847 patent is an improved, useful binder, such a binder is commercially desirable only if it can be manufactured inexpensively and in volume numbers. Such a manufacturing operation desirably requires a minimum number of manual operations or, in other words, a maximum amount of mechanization.

The present invention is apparatus designed to manufacture and assemble a binder of the type disclosed in the No. 3,175,847 patent. Additionally, the present invention may be utilized for the manufacture of numerous other types of binders.

SUMMARY OF THE INVENTION

In a principal aspect, the present invention comprises an improved mechanized apparatus for the manufacture of a binder of the type including a case, at least one spine member, a metal and fastening means for fastening the metal and spine to the case. The apparatus includes means for making openings in the case at a desired position, means for then positioning the spine against the case to cooperate therewith, means for sub-

sequently positioning the metal in cooperation with the spine and the case and means for securing the metal in cooperation with the spine and case.

It is thus an object of the present invention to provide an improved apparatus for the manufacture of a binder.

It is a further object of the present invention to provide apparatus for the manufacture of a binder which automatically fabricates the components of the binder into a finished product without any manual fabrication operations.

Still another object of the present invention is to provide apparatus for the manufacture of the binder, which apparatus is operable at high speeds and at the same time is reliable.

One further object of the present invention is to provide an apparatus for automatic manufacture of a binder of the type which includes a case, at least one spine member, a metal and fastening means for holding the metal and spine member in cooperative relationship with the case.

Still a further object of the present invention is to provide an improved apparatus for the manufacture of a binder including means for precisely positioning and attaching a spine member and a metal to the case of a binder.

One further object of the present invention is to provide apparatus for the manufacture of a binder, which apparatus operates in sequential steps to perform the manufacturing operation of the binder without the intervention of manual operations.

These and other objects, advantages and features of the present invention will be set forth in greater detail in the description which follows.

BRIEF DESCRIPTION OF THE DRAWING

In the detailed description which follows, reference will be made to the drawings comprised of the following FIGURES:

FIG. 1 is a perspective view of a typical assembled binder;

FIG. 2 is an exploded, perspective view of a binder of a type which the apparatus of the present invention may be utilized to fabricate;

FIG. 3 is a partial, perspective view of the configuration of the spine members included in a binder of a type shown in FIG. 2;

FIG. 4 is an end view of a binder of the type shown in FIG. 2;

FIG. 5 is a schematic, plan view of the arrangement of the operating stations of the apparatus of the present invention;

FIG. 6 is a schematic, perspective view of the stations and operation of the improved apparatus of the present invention;

FIG. 7 is a perspective view of the apparatus of the present invention illustrating the entire assembled apparatus;

FIG. 8 is a graphical representation of the sequence of operations performed by the apparatus of the present invention;

FIG. 9 is a partial, perspective view illustrating the first station of the apparatus of the invention, which station is utilized to precisely punch openings in the case of the binder;

FIG. 10 is a perspective view of the underside of the apparatus shown in FIG. 9;

FIG. 11 is an electrical schematic showing the control circuitry for the first station of the improved apparatus of the present invention;

FIG. 12 is a cross-sectional view of the punch and alignment mechanism of the first station of the present invention taken substantially along the line 12-12 in FIG. 9;

FIG. 13 is a cut-away elevation of the drive and control cam arrangement of the second station of the present invention which is utilized to precisely position the spine members of the binder in cooperation with the case of the binder;

FIG. 14 is a cross-sectional view of the apparatus shown in FIG. 13 taken substantially along the line 14-14;

FIG. 15 is an enlarged, perspective view of a portion of the apparatus shown in FIG. 14 utilized to position a cover sheet for the spine in relation to the case of the binder;

FIG. 15A is a partial diagrammatic view of the case in feed mechanism of the second station;

FIG. 16 is a side view of the portion of the apparatus shown in perspective in FIG. 15;

FIG. 17 is a perspective view of the plate incorporated as a portion of the apparatus shown in FIG. 15, which plate is utilized to transport a cover member for the spine of a binder;

FIG. 18 is a cross-sectional view of the pocket construction which comprise a portion of the second station illustrated in FIG. 13;

FIG. 19 is a series of twelve schematic figures illustrating the operation of the second station illustrated in FIG. 13;

FIG. 20 is a partial, perspective view of the apparatus of the second station which positions the spine members of the binder in cooperation with the case of the binder;

FIG. 21 is an enlarged, perspective view of the arrangement utilized to position the spine members of the binder in cooperation with the case, this arrangement having been previously illustrated in cross-sectional view in FIG. 18;

FIG. 21A is a cross-sectional view of the pocket assembly of the second station;

FIG. 22 is a cross-sectional view taken substantially along the line 22-22 of FIG. 20;

FIG. 23 is a cross-sectional view of the construction utilized to position one spine member in cooperation with the case of the binder taken substantially along the line 23-23 in FIG. 20;

FIG. 24 is an elevational view of the mechanism utilized to position the spine cover against a spine member at the second station of the apparatus;

FIG. 25 is a perspective view of the mechanism utilized to operate a compression driving member against the spine members of the binder, and thus maintain the spine members in a fixed position in conjunction with the case of the binder;

FIG. 26 is a perspective view of the mechanism for transporting the case and associated spine members from the second station of the apparatus taken substantially along the line 26-26 of FIG. 13;

FIG. 27 is a perspective view of the third station shutter mechanism for positioning a metal in cooperation with the spine members of a binder;

FIG. 28 is a perspective view of the fourth station riveting mechanism utilized to attach the metal to the spine of the binder; and

FIG. 29 illustrates in perspective a plurality of binders manufactured by the apparatus of the present invention and stacked in a box by stacking means.

DESCRIPTION OF THE PREFERRED EMBODIMENT

As previously mentioned, the preferred embodiment of the apparatus of the present invention is utilized to manufacture a binder of the type disclosed in McKowen U.S. Pat. No. 3,175,847. U.S. Pat. No. 3,175,847 is incorporated herewith by reference. This binder is generically described in the art as a three-piece binder and is illustrated in FIG. 1 in its finished configuration. FIG. 2 is an exploded view of the components which comprise the particular binder which the preferred embodiment of the present invention is designed to manufacture.

Specifically, the separate parts of the binder include a case 10, an outer spine 12, an inner spine 14, a cover sheet 16 for the outer spine, a metal 18, and a pair of rivets 20 and 22 which are utilized to fasten the entire assembly together.

The cover 10 may be fabricated in any of a number of ways. Typically, the cover 10 includes a flexible center section 24 with stiff side board sections 26 and 28 on opposite sides of the center section 24 to form the hard covers of the binder. A plurality of four openings 31, 32, 33 and 34 are defined along a center line axis of the center section 24. The openings 31-34 are adapted to receive rivet studs 41 and 44 and spine binding studs 42 and 43 of outer spine 12. The outer spine 12 as well as the inner spine 14 are typically fabricated from a plastic material.

The inner spine 14 likewise includes four stud openings 51-54 adapted to receive the studs 41-44 respectively. During assembly of the binder, the spine binding studs 41 and 43 are positioned through openings 32 and 33 of center section 24 thence through openings 52 and 53 of inner spine 14. Studs 41 and 43 then are compressed to lock the spine members 12 and 14 together on opposite sides of the center section 24. The metal 18 is then positioned over the inner spine so that metal openings 61 and 64 respectively cooperate with studs 41 and 44. The rivets 22 and 20 are next positioned through the openings 61 and 64 respectively to cooperate with the studs 41 and 44 respectively and hold the entire assembly in a fixed finished configuration.

As an optional and additional feature of the binder which is manufactured by the preferred embodiment of the apparatus of the present invention, the cover sheet 16 is positioned about the outer spine 12 in the manner illustrated in FIG. 3. That is, the cover sheet 16 includes a center portion 66, a first outside fold 68 and a second outside fold 70. Typically, the cover sheet 16 will be a cloth or a plastic type material having, perhaps, decorative printing or markings thereon so that the outer spine of the binder will be provided with a decorative covering.

The folds 68 and 70 are flexible. Each fold includes openings as at 72 and 74 respectively which permit the folds 68 and 70 to be positioned over the stud 44 and flat against the inside surface of the outer spine 12. It will also be noted in FIG. 3 that the stud 44 includes a center passage 76 to facilitate the positioning of the

rivet 20 in cooperation with the stud 44 as described below.

In the end view of FIG. 4, the binder construction is illustrated in an assembled configuration. As shown, the rivet 20 cooperates with the stud 44 so that the rivet 20 is securely held by the stud 44. This is due in part to the fact that the stud 44 is fashioned from a plastic material which tends to grip the rivet 20 subsequent to driving the rivet 20 into the stud 44. Referring again to FIG. 2, the spine binding stud 43 just extends through the opening 53 of the inner spine 14 so that the stud 43 can be flared by means of heat, compression, or heat and compression to rigidly secure the components of the binder together.

The foregoing has been a detailed description of the binder as manufactured by the disclosed preferred embodiment of the present invention. Although the disclosure discusses a preferred embodiment for manufacturing a particular binder, the scope of the invention is not to be limited to either the apparatus to manufacture this particular binder or the specific apparatus described.

I. Brief Detailed Description

Now referring to FIGS. 5, 6 and 7, there is illustrated in various manners the construction and arrangement of the entire apparatus comprising the invention. In FIG. 5, a schematic plan view illustrates the layout of the apparatus of the invention. The work stations of the invention are sequentially numbered 1 through 4. Station 1 will hereinafter be termed the punch station. Station 2 will hereinafter be termed the spine station. Station 3 will hereinafter be termed the metal station. Station 4 will hereinafter be termed the rivet station. The binder is manufactured in sequential steps as it moves from station 1 through station 4.

FIG. 6 illustrates this arrangement in greater detail. FIG. 7 is a complete perspective view of the entire binder manufacturing apparatus. The following discussion will briefly set forth the arrangement of each station of the invention by referring to FIGS. 6 and 7. A more detailed description will then be provided for each station.

A. Punch Station

The punch station 1 includes a magazine 82 which is filled with a plurality of cases 10 stacked one upon the other. The cases 10 are stacked adjacent a platform 84. A plate 86 driven by a hydraulic cylinder 88 and attached linkage 90 slides back and forth beneath the stack of cases 10 thereby discharging a single case from the magazine 82 to a position on the platform 84 beneath a punch 92. Once the case is positioned beneath the punch 92, appropriate sensing circuitry causes the punch to operate, thereby precisely punching the openings 31-34 in the case 10. As an optional feature of the punch station, a glue dispenser 94 will apply desired amounts of glue to the underside of the case 10. In the following description, it should be kept in mind that the underside of the case 10 coincides with the outside of the finished product binder.

Subsequent to application of the glue to the case and punching of the opening 31-34 in the center section of one case 10, the plate 86 drives another case 10 onto platform 84. This second case 10 engages and drives the punched case 10 onto a conveyor 96. The conveyor 96 then operates to transport the punched case 10 to the second or spine station 2.

B. Spine Station

At the spine station 2, a single cover sheet 16 from a stack of cover sheets is transported by means of a transport mechanism 152 to a central station position or pocket assembly 154. Next, the outer spine 12 is transferred from a magazine of outer spines (not shown) via an outer spine transport arm mechanism 156. The outer spine 12 is positioned over the cover sheet 16 and a folding arm mechanism (not shown in FIGS. 6 and 7) bends the outside folds 68 and 70 of cover 16 about the outer spine 12.

Next, the case 10 is conveyed over the central station position with the center section 24 of the case 10 aligned so that the studs 41-44 of the outer spine 12 extend through the appropriate openings 31-34 punched at the punch station 2. Then, an inner spine arm transport mechanism 158 transports an inner spine 14 over the center section 24 of the case 10. An anvil 160 holds the spine members 12 and 14 and case together and punches as at 162 and 164 compress studs 42 and 43 to lock the spine members 12 and 14, case 10 and cover 16 together. The binder is then conveyed to the metal station 3 via a conveyor.

C. Metal Station

At the metal station 3, a magazine 166 discharges a single metal 18 over the inner spine 14 of each binder. The studs 41 and 44 tend to hold the metal 18 in a fixed position once the metal 18 is positioned on the inner spine 14. The binder is then transported to the final assembly station or rivet station 4.

D. Rivet Station

At the rivet station 4, the metal 18 is gripped into position against the binder and rivets 20 and 22 are discharged and hammered into the appropriate studs 41 and 44 by means of hammer mechanisms 352 and 354. The finished binder is then released from the rivet station 4 and discharged by means of a conveyor from the apparatus.

II. Complete Detailed Description

In the following detailed discussion each of these four stations will be discussed serially in detail during the discussion, reference will be made to FIG. 8 which sets forth a graphical representation of the sequential operation of the various stations. Also, during the discussion, reference will be made to FIGS. 9-12 relative to the punch station 1; FIGS. 13-26 relative to the spine station 2; FIG. 27 relative to the metal station 3; and FIG. 28 relative to the rivet station 4.

A. Punch Station

As shown in FIGS. 5, 6 and 7, the punch station 1 is the first station for the apparatus. FIGS. 9 and 10 illustrate a partial perspective view of the punch station 1. The magazine 82 is comprised of four vertical guide arms 101-104. The case 10 of a binder is positioned in these guide arms with the outside of the case 10 facing downward. The case 10 is stretched out in a flat position for engagement by the plate 86 which slides over the platform 84 via linkage 90 in response to operation of cylinder 88. Plate 86 pushes a single case 10 to a position beneath the punch 92. Simultaneously, a case 10 previously beneath punch 92 is discharged onto the conveyor 96.

The punch 92 includes a guide plate 106 slidably mounted on four guide rods 108-111. The guide rods 108-111 are mounted on case guides 113 and 114. The guides 113 and 114 serve to align the case 10 in a fixed position beneath the punch 92. A drive rod 116 is rigidly attached to the plate 106 and is driven in response

to a signal to a coil 115 mounted in a fixed position over the plate 106. Thus, when an electric signal activates the coil 115, the rod 113 causes the plate 106 and attached punches 117, as illustrated in FIG. 12, to descend through the center portion of a case 10 positioned beneath the plate 106.

Referring to FIG. 12, it can be seen that the plate 106 includes a series of punches as at 117 cooperative with punch openings as at 119 in plate 84. The punches 117 thus cooperate with openings 119 to provide complete shearing of the material comprising the case 10. As illustrated in FIG. 12, the punch 117 may be replaced by removing a threaded retaining nut 121 which holds the flanged punch 117 in position in the plate 106. In this manner, the length of the punch 117 may be controlled depending upon the requirements. Also, it is easy to replace a broken punch with this construction.

FIG. 11 discloses a control circuit for the punch station. Power is supplied by input lines 123 and 124. The power supply is fused by fuse 125 and a console start switch 126 is provided to activate the punch station. The switch 126 is mounted in a panel 128 as illustrated in FIG. 7. Once the switch 126 is activated to close the circuit, a telltale light 129 operates to indicate that the punch station 1 is activated.

Upon activation of the switch 126, a normally closed relay 130 remains in its closed position. A second normally open micro-switch or relay 131 also closes when a conveyor feed for the spine station 2 reverses indicating a case 10 has been delivered from the punch station 1 into the spine station 2. Thus, when the relay 131 is closed, power is supplied to control a control solenoid 132F associated with the pneumatic input to the cylinder 88. The cylinder 88 is then operated to drive its rod 89, attached linkage 90 and thus the plate 86 forward through the magazine 82, thereby driving a case 10 to a position beneath the punch 92.

When the case 10 has reached a position beneath the punch 92, a position-sensitive micro-switch opens the normally closed relay 130 and closes the normally open relay 133. Relay 133 operates the coil 115D associated with the punch 92 to drive the punch 92 in the vertically descending direction. This causes the punch 92 to make the openings 31-34 in the case 10.

At the end of the punch stroke, a position-sensitive switch closes the normally open relay 134 which causes the coil 115U to drive the rod 113 in a vertically ascending direction. Simultaneously, the coil 132B associated with the cylinder 88 is actuated as described above to return plate 86 to its original position. Each of the position-sensitive relays responds to the position of the plate 86 or punch plate 106 as they move through their cycle of operation.

The punch cycle then commences again with a case 10 being positioned over the conveyor 96 as another case is positioned below punch 92.

Upon demand then, the cycle of switching will commence and continue in the manner described above. The cases 10 are thus punched one at a time in the center portion 24 and are delivered via the conveyor 96 to the spine station 2 of the device.

Referring to FIG. 9, as a case 10 is placed over conveyor 96, a series of pivotal, parallel bars 98 mounted on a bracket comprised of rods 97 connected to cross braces 100 support the case 10 above the conveyor. Only one cross brace is shown, although a parallel brace 100 is provided. Bars 98 pivot about rods 97 as

an axis. When the coil 132B operates to retract plate 86, a coil 140 is also energized to operate a solenoid 143. The solenoid 143 moves a lever arm 144 to pivot the bars 98 in a counterclockwise direction. The case 10 thus drops uniformly onto the conveyor 96. Simultaneously, with the energization of coil 140, which is part of a contactor 141, a clutch coil 138 is energized. When the clutch coil 138 is energized, a mechanical coupling is effected between a continuously operating motor 136 and the conveyor 96. This causes the conveyor 96 to commence operation by moving in the direction of the arrow in FIG. 9.

The conveyor 96 includes stops 99 which drive the case 10 to the spine station 2. As the case 10 approaches the proper position relative to the spine station 2, a travel limit relay 135 in FIG. 11 is operated to de-energize the coil 140. The solenoid 143 is thus de-energized to cause the rods 98 to assume their original position illustrated in FIG. 9. The conveyor 96 also ceases to operate since the clutch coil 138 is de-energized.

An optional gluing operation is possible as illustrated in FIG. 10. There the glue nozzle 94 is positioned beneath the case 10 and plate 86. The glue nozzle 94 is positioned to lay down a strip of glue along the back outside center portion 24 of the case 10 as case 10 is being transported into position beneath the punch 92. Typically, a glue gun system of the type sold by the Fox Division of The Aro Corporation can be utilized.

In the described embodiment, the operation of the glue gun 94 is controlled by a cam 145 mounted on plate 86 as illustrated in FIG. 9. Cam 145 energizes a micro-switch 146 as the plate 86 traverses a path to place the case 10 under punch 92. That is, a follower 146A of switch 146 responds to cam 145 to operate the glue gun 94. As the micro-switch 146 completes a circuit, the glue gun system commences operation for a pre-set period of time and discharges glue onto the moving case 10. Thus, the micro-switch 146 is operated each time it engages an indentation on the cam 145 whenever the cam is moved in a forward direction to drive a case under the punch 92.

B. Spine Station

Referring to FIG. 7, the spine station 2 is positioned to receive a case 10 from the punch station 1. FIGS. 7, 8 and 13-25 illustrate the construction of the spine station 2.

Referring to FIGS. 7 and 13, spine station 2 is mounted on a frame 170 which is positioned intermediate the punch station 1 and the metal station 3. A single electric motor 172 is mounted on the frame 170 and is operative through a clutch 173 and a transmission 174 to drive a shaft 175. The shaft 175 has a plurality of attached cams and gears which through various mechanical linkages operate the spine station 2.

The shaft 175 is mounted for rotation in bearings 176, 177 and 178. Rigidly attached to the shaft 175 and operative to rotate in unison with the shaft are a plurality of gears or cams as follows: barrel cam 180 which is linked to operate a mechanism for transferring a cover 16 into position in the spine station 2; sprocket 181 (also illustrated in FIG. 14) which is operative to raise and lower a head assembly associated with fastening the spine members 12 and 14 together; cam 182 (illustrated in FIGS. 14 and 20) which is operative to feed in the outer spine member 12 into position in the spine station 2; cam 183 which is operative to raise or lower

a vacuum tube arrangement associated with the outer spine positioning mechanism; a cam 184 which is operative to move a pocket assembly in which the cover 16 and spine 12 are positioned; cam 185 which is associated with the vacuum tube arrangement for positioning the inner spine member 14; cam 186 which operates the carrier mechanism operative to feed an inner spine member 14 into position in the spine station (also illustrated in FIG. 20); cam 187 which operates through a linkage to move the case 10 into position within the spine station 2; cam 88 which is operative to remove the case 10 from the spine station 2; a second barrel cam 189 which is operative to transport a head assembly into and out of position over the center of the spine station during the operation of the spine station; and a sprocket 190 which drives a chain 191 that, in turn, drives another sprocket 192. Sprocket 192 is operative to rotate a shaft 193. The shaft 193 has a plurality of cams 194-199 mounted thereon. As the cams 194-199 are rotated they sequentially operate switches 200-205 respectively to thereby control operation of vacuum lines associated with the spine station 2 in the manner to be described below. As illustrated in FIG. 13, the product flow or flow of the case 10 is from right to left substantially along the flow line 207. The sequence of operation of the spine station 2 will now be discussed in the context of the order of the operations performed by the spine station 2.

First, it is to be remembered that a case 10 has been positioned adjacent the spine station 2 by the conveyor 96 from the punch station 1. Before the case 10 is fed into the spine station 2, it is necessary to position a cover 16 and an outer spine member 12 in a center pocket 210 of the spine station 2. This sequence of operation is illustrated in FIG. 19(A).

As illustrated in FIG. 19 and also by referring to FIGS. 15, 16, 17 and 21, the pocket 210 which is positioned in a center portion of the spine station 2 has associated therewith a head 211 to be more fully described below. A cover transfer plate 212 is also associated therewith and includes a plurality of vacuum ports 213 as illustrated in FIG. 17. The plate 212 is thus positioned against a cover 16 positioned in a magazine 214.

Magazine 214 is slidably mounted on rods 214A and 214B. A member 214C is biased by springs 214D to engage magazine 214 and position the magazine 214 in snug communication with plate 212 as shown in FIG. 15. Additional covers 16 may be placed in magazine 214 by manually moving the magazine 214 against the spring 214D and inserting covers 16 into the magazine 214.

The vacuum ports 213 of plate 212 are activated through a vacuum line 215 to provide a slight vacuum pressure on the cover 16. Vacuum to the vacuum line 215 is initiated by operation of cam 194 and operating switch 200 illustrated in FIG. 13 which in turn operates as shaft 175 is rotated.

The plate 212 is then transferred along the path illustrated schematically in FIGS. 15 and 19(A) so that the cover 16 is likewise transferred from the cover magazine 214 to a position directly over the pocket 210. The transfer of the plate 212 is accomplished by the linkage illustrated in FIGS. 13, 15 and 16.

Referring first to FIG. 13, a follower 216 is associated with a linkage arm 217. The follower 216 follows a cam track 218 in the barrel cam 180 as the barrel cam 180 is rotated by virtue of rotation of the shaft 175. Linkage

arm 217 is pivoted about a pivot axis 219 and operates, in turn, to drive a rack 220 through a rod 221 and arm 221A in the manner illustrated in FIG. 16. The rack 220 drives a pinion 222 which is, in turn, attached to a plate support arm 223. The plate 212 also has a second plate support arm 224 pivotally attached thereto.

As illustrated in FIGS. 15 and 16, the plate 212 has a first side designated by the letter A and an opposite, parallel side designated by the letter B. The linkage 10 mechanism just described transfers the plate from the magazine 214 illustrated in FIG. 15 to the position shown in phantom in FIG. 15 and FIG. 16. When so transferred, the plate 212 operates to place the cover 16 over the pocket 210, the pocket 210 being mounted 15 in between bed plates 225A and 225B as illustrated in FIG. 21. As the plate 212 positions the cover 16 over the pocket 210, a release valve 226 for the vacuum lines 215 engage a stop (not shown) on bed 225B to quickly bleed air into lines 215 and release the vacuum 20 in the ports 213. This causes the cover 16 to be deposited onto the beds 225A, 225B and pocket 210. The barrel cam 180 then continues on its rotational cycle thus removing the plate 212 from over the pocket 210, as illustrated in FIG. 19(B). Simultaneously, with release of cover 16 by ports 213, a vacuum is applied to the cover 16 through ports 256 via lines 255 as a result of operation of the cam 196 on the valve switch 203. This is indicated symbolically in FIG. 19(B) by the letter V and the arrows associated with the cover 16 and 25 is further illustrated in FIG. 21.

Simultaneously, the head mechanism 211 is positioned over the pocket 210. As shown in FIG. 13, this positioning is effected by a cam track 228 of the rotating barrel cam 189. A cam follower 229 for track 228 30 is attached to a linkage arm 230 and is pivotal about a shaft 231. Arm 230 acts through a linkage rod 233 and drives a translatable carriage 232 as shown in FIG. 26. The carriage 232 is thus translated on rods 253 and 254 to the right in FIG. 26 and FIG. 13 so that the head 211 35 is positioned over the pocket 210 as illustrated in FIG. 19(C).

Simultaneous with positioning of the head 211 over the pocket 210, the outer spine member 12 is also positioned over the cover 16 as illustrated schematically in FIG. 19(C). The mechanism for feeding in the outer spine 12 is illustrated in detail in FIG. 14 and FIG. 20. This mechanism includes the cam 182 which rotates on the shaft 175. The cam 182 includes an activating lobe 235 which is followed by a follower 235A. The follower 235A is attached to a biased gear segment 236. The gear segment 236 is pivotal about a shaft 237 and cooperates with a pinion 238 on a shaft 238A. Rotation of pinion 238 causes a like rotation of pinion 239A which, in turn, drives a chain 239. The chain 239 extends over idler gears 239B, 239C and 239D and is attached to a pair of carriage arms 240 and 241. The carriage arms 240 and 241 may be moved to the right in FIG. 20 to the position shown in FIG. 14 by the chain 239 and thus 45 position an outer spine 12 over the pocket 210.

The outer spine 12 is placed on the carriage arms 240 and 241 from a magazine 242 for the outer spines 12 shown in FIGS. 7 and 20. This arrangement employs the cam 183 (in FIG. 20) which had associated therewith a follower 243 attached to a pivoted linkage arm 244. Linkage arm 244 is pivoted about pivot point 245 and operates to drive a rod 246 which, in turn, raises and lowers a vacuum plate assembly 247.

The vacuum plate assembly 247 includes a vacuum plate 248 positioned on a mounting bracket 249. A flexible vacuum hose 250 connects with the vacuum plate 248 and with a plurality of vacuum tubes 251. Prior to driving the arms 240 and 241 into position over the pocket 210 the cam 183 operates to drive the rod 246 and vacuum assembly 247 upward so as to engage an outer spine 12. The vacuum tubes 251 are then provided with vacuum pressure through the hose 250 upon contact with the outer spine 12. This negative pressure is effected by cam 195 operating valve switch 210 for line 250 in FIG. 13. The outer spine 12 is pulled from the magazine 242 and downward as rod 246 is moved downward toward the arms 240 and 241. Upon reaching the arms 240 and 241, the vacuum is released by operation of cam 195. In this manner, an outer cover is placed on the arms 240 and 241 ready for positioning over the pocket 210. The arms 240 and 241 then proceed to place the spine 12 over the pocket 210 in the manner previously described.

After the spine 12 is placed over the pocket 210, the head 211 is made to operate and drive the spine 12 between the arms 240 and 241 and into the pocket 210. This is illustrated schematically in FIG. 19(D) and FIG. 19(E) wherein the head 211 is driven downward to engage the spine 12 and the cover 16. It should be noted that during this sequence of operation the cover 16 is maintained in position by vacuum ports in contact with the cover 16. This prevents the cover 16 from sliding out of position over the pocket 210, particularly when the spine 12 is driven downward into engagement therewith. This vacuum arrangement is illustrated in greater detail in FIG. 21 and was discussed, in part, above.

Referring to FIG. 18, FIG. 21, and FIG. 21(A), the pocket 210 is supported on a pocket support rod 260. The pocket support rod 260 may be operated to move the pocket 210 up and down as required into and out of a position between the beds 225A and 225B. The pocket 210 is moved upward by the cam 184 in FIG. 13. The cam 184 directly engages a follower (not shown) attached to the rod 260 to drive the pocket upward or to permit downward movement of the pocket 210 since the pocket 210 is biased downward by a spring (not shown) attached between pocket 210 and the frame 170.

Referring to FIG. 19(F), it will be seen that once the outer spine 12 and cover 16 are positioned in the pocket 210 by the head 211, they are retained in position by vacuum ports 257 in FIG. 21A of pocket 210 and ports 256 of beds 225A and 225B. This maintains the cover 16 in position in the pocket 210.

The structure for maintaining the spine 12 in the pocket 210 is depicted in FIG. 21A. The pocket 210 is movable on the rod 260. Attached pivotally to the end of the pocket 210 is a plate 216. The outside of the plate 216 includes an inclined cam 262 which is adapted to engage a fixed cam 263. Cam 263 is attached to the frame 170 of the apparatus. During operation of the spine station 2 as illustrated in FIG. 19(F), the rod 260 causes the pocket 210 to be lowered. As this occurs, the cam 262 engages the fixed cam 263 driving the plate 216 about its pivotal axis and against the spine member 12 in the pocket 210.

It will be noted that the pocket 210 has a curvature substantially identical to the curvature of the spine 12. With the ends of the spine 12 engaged by and held be-

tween the plate 216 at each end of pocket 210, the pocket 210 may be lowered even further. As the pocket 210 is lowered, it causes the cover 16 to be drawn between the beds 255A and 255B. This causes the flaps or edge portions of the cover 16 to be folded upward. This upward folding action is assisted by removal of vacuum through the passages 255.

After the pocket 210 is lowered, the side flaps or folds 68 and 70 of the cover 16 are folded over the outer spine 12. This is illustrated schematically in FIGS. 19(G) and 19(H). The apparatus utilized to achieve this folding motion is illustrated in greater detail in FIG. 24. Referring to FIG. 24, a pair of fold-over plates 264 and 265 are positioned on opposite sides of the pocket 210 and are pivotal about shafts 266 and 267 respectively. Each plate 264 and 265 is comprised of an arcuate sheet 268 and 269 respectively which is adapted to engage one side or the other of the cover 16. Each sheet 268 and 269 respectively is, in turn, attached to spring biased arms 270 and 271. Thus, the arm 270 is biased by a spring 273 in a counterclockwise direction about the shaft 266. A cam surface 274 of the arm 270 engages a follower 275 attached to the end of a rod 276.

The sheet 268 extends the length of the pocket 210. Thus, upon engagement of the follower 275 with the cam surface 274 to bias the arm 270 against the spring 273, the sheet 268 will be caused to move about the axis 266 in a clockwise direction and engage the flap 68 of cover 16 in the manner shown in FIG. 19(G). The fold-over plate 265 operates in substantially the same manner and operates to fold over the opposite flap 70 of the cover 16 as schematically illustrated in FIG. 19(H).

It should be noted that the fold-over plates 264 and 265 fold the flaps 68 and 70 so that the punched flap openings, illustrated in FIG. 2, fit over the spine projections 41-44 in FIG. 2. This locks the cover 16 in a fixed rigid position about the outer spine 12.

The plate 265 is driven by the following described mechanism. The rod 276 is driven in response to a cam 184A attached to rotate coincidentally with cam 184 as shown in FIG. 13 and FIG. 24. Cam 184 drives a follower path 184C and thus the rod 276 as shown in FIG. 24. Another cam 184B on shaft 175 and also rotating coincidentally with cam 184 operates to drive fold-over plate 264 in a similar manner.

The next operation performed by the spine station 2 is movement of the case 10 into position over the pocket 210. Attention is directed to FIGS. 7, 13, 15A and 19 wherein (particularly in FIG. 15A) there is illustrated a means by which the case 10 is positioned over the pocket 210. This means includes a pusher assembly 278 which is mounted on a chain 294. The pusher assembly 278 engages a case 10 and drives it in the direction of path 207 into a precise position over the pocket 210. Simultaneously, the pocket 210 is raised by operation of the support rod 260 so that the spine 12 and cover 16 are brought into position against the center back portion 24 of the case 10. This is illustrated schematically in FIG. 19(I).

The pusher assembly 278 is operated in response to the operation of cam 187 by a mechanical linkage in frame 170. FIG. 15A is a diagrammatic view of this mechanical linkage which drives pusher 278 in response to rotation of cam 187. The cam 187 rotates on the shaft 175. A follower 281 is mounted on a pivoted arm

282 and causes the arm to rotate about pivot point 283. This drives a rack 284 which, in turn, turns a pinion 285 attached to a shaft 286. The shaft operates bevel gears 287 to drive a second shaft 288 that, in turn, drives a pinion 289 and chain 290. The chain 290 is connected to another pinion or gear 291 which turns a shaft 292 operating still another pinion 293. A link chain 294 passes over pinion 293 and a second idler gear 295 on a shaft 296. The shafts 292 and 296 are mounted in frame 170 perpendicular to the direction of travel of the case 10 and are positioned so that the pusher assembly 278 which is attached to the chain 294 will be properly positioned to push the case 10 over the pocket when the desired operation is effected by movement of the cam 187. Thus, movement of the rack 284 in conjunction with the pinion 285 causes the pusher assembly 278 to be driven inward or to be reversed in direction to thereby move the case 10 in position relative to the pocket 210. As previously stated, this final position of case 10 is illustrated by FIG. 19(I).

The next operating sequence of the apparatus involves movement of the inner spine member 14 into position over the case 10. This is illustrated schematically also in FIG. 19(I) as well as FIG. 20 and FIG. 23. There arms 298 and 299 are operated to position the inner spine 14 over the case 10. The operation of the inner arms 298 and 299 as well as the vacuum associated therewith is substantially identical to that previously described for the outer spine 12. That is, cam 186 like cam 182 operates to drive the arms 298 and 299 and cam 198 operates the vacuum associated with inner spine 14. Cam 185 operates to position vacuum plate 247 associated with arms 298 and 299. Thus, like parts of the inner spine 14 positioning mechanism have been numbered the same as those for the outer spine 12 except for the addition of the suffix I to the number. Further description if not deemed necessary.

Along with the positioning of the inner spine 14 over the case 10, the head 211 is again brought into position by cam 184 in the manner previously described and as schematically shown in FIG. 19(I). The head 211 is then made to drive the inner spine 14 downward against the case 10 and the outer spine 12 into the pocket 210. This is illustrated schematically in FIG. 19(J). It should also be noted in FIG. 19(J) (which corresponds to FIG. 18) that the pocket 210 is moved downward a short distance between the support bed 255A and 225B.

As illustrated in FIG. 14, the head 211 is lowered by operation of a cam 400 on a shaft 401 driven by a pinion 402. Chain 403 drives pinion 402 and, in turn, is driven by gear 181 on shaft 175. The cam 400 engages roller follower 404 on head 211 and drives the head down against the biasing force of springs in the carriage 232 (in FIG. 26) which carries the head 211. Thus, the head is lowered as required whenever carriage 232 is positioned so that cam 400 engages follower 404.

FIG. 21 illustrates the position of the head 211 relative to the assembled components of the case just subsequent to positioning of the inner spine member 14 and before the head 211 is lowered completely. The projections 41-44 of outer spine 12 are positioned for interaction with the head 211.

Referring to FIGS. 14, 18 and 25 as well as FIG. 21, the head 211 includes a pair of rods 302 and 303 which are positioned for intersection with the projections 42 and 43. The rods 302 and 303 are biased by a spring as

at 304 in FIG. 18 into a retracted position. This spring 304 is also illustrated in FIG. 25. After the head 211 is appropriately lowered against the case 10 and inner spine 14 as illustrated in FIG. 19(J), a hydraulic piston 306 is actuated by operation of a projection 307 attached to cam 400. The cam 400 is, of course, the cam attached to and associated with a follower 404 for the head 211.

Thus, operation of the piston 306 drives a rod 312 and its attached follower 313 to engage pivoted arms 314 and 315. Arms 314 and 315 are attached to fixed shafts 316 and 317 respectively. Attached to the shafts 316 and 317 respectively are cams 318 and 319 respectively. The cams 318 and 319 engage and drive rods as at 302 downward (as illustrated in phantom in FIG. 25) to impinge upon a projection as at 42 and thus flatten the projection against the inner spine 14 thereby locking the spine members 12 and 14 of the binder together. The rod 312 then quickly retracts to release the drive rod 302. The rod 302 may be heated to facilitate the action of spreading the projection 42 into a locking relationship over the inner spine member 14.

As can be appreciated by reference to FIG. 21, the head 211 includes openings 410 and 411 for studs 41 and 44 to prevent damage to said studs 41 and 44. Head 211 also includes vacuum ports 414 which are operated by cam 197 and associated valve switch 203 as indicated in FIG. 8.

Subsequent to the attachment of the spine members 12 and 14 in a tight configuration with relation to the case 10, the assembly steps performed at the spine station 2 are complete. The head 211 is then moved out of position by operation of the cam 189 in the manner previously described for moving the head 211 and the pocket 210 raises slightly as depicted in FIG. 19(K). As the head 10 is moved out of position, an out-take mechanism grasps onto one side of the case 10 as illustrated in FIG. 19(L) and removes the case 10 in its assembled configuration from the spine station 2. Removal of the case 10 is effected by cam 188 which operates a mechanical linkage and chain substantially identical to the infeed linkage illustrated in FIG. 15A. The out-take mechanism of course operates to position a grasping mechanism in contact with the case 10 and then drives a chain in the direction of case travel along axis 207 of FIG. 13.

As illustrated in FIG. 26 an out-take chain 222 includes rollers 223 thereon. As the chain 222 is driven in a clockwise sense by the linkage associated with cam 188, the rollers 223 are permitted to roll freely over the case 10 as the chain passes under the case 10. The rollers 223 are spring biased to engage the case 10. The rollers 223 also include a clutch mechanism which enables the rollers 223 to roll onto the case 10 when the chain 222 is moving in a clockwise direction. However, when the chain 222 moves in a counterclockwise sense the rollers 223 do not roll. Thus, they grasp the case 10 and pull it from the spine station 2 toward the metal station 3.

Reference is directed to FIG. 8 which illustrates the sequence of operation and operation of the cams which perform the functions of the spine station 2. The horizontal axis indicates the degree of rotation of the shaft 175. The vertical axis includes a definition of the various operations performed by the spine station and an indication of when those operations commence in accordance with the movement of the cam associated

therewith. The lower portion of FIG. 8 includes an identification of the operation of the valve switches associated with the vacuum line to thereby provide for a vacuum at the various indicated stations in the figure. Thus, by reference to FIG. 8, it is possible to determine accurately the shape required of the cams for performing the various operations whether those operations be a mechanical positioning of some component or the opening or closing of a valve associated with a vacuum line.

By way of example, the guide bars or rods 240 and 241 which are operative to position the outer spine member 12 in position in the spine station are identified in the left-hand column of FIG. 8. These guide bars 240 and 241 commence to move into position over the pocket 210 at 60° rotation of shaft 175. The guide bars 240 and 241 remain in position over the pocket 210 until the shaft 175 is rotated to approximately a 150° position. In the meantime, the head 227 commences operation at approximately the 80° position and moves down as indicated on the graph and then moves up as further indicated on the graph holding at the up position thereby accomplishing the objective of positioning the outer spine member 12 in the pocket 210. Later as will be noted in the sequence of operation, the head 227 again moves down. This is for the purpose, of course, of positioning the inner spine 14 in position in the pocket.

C. Metal Station

FIG. 27 illustrates the third station of the apparatus or the metal station 3. This was previously described in general fashion and indicated in FIG. 7. The metal station 3 includes the magazine 166 having a plurality of metals 18 therein. A shutter mechanism 325 is positioned intermediate the vertical ascending portion of the magazine 166 and a binder conveyor 326 for the metals 18. After the case 19 is removed from the spine station 2 by the out-take mechanism, the case 10 with its assembled spine members is transferred onto the conveyor 326. Conveyor 326 accurately indexes and positions the case 10 directly beneath the magazine 166. As the case is positioned appropriately beneath the magazine 166, a microswitch (not shown) is triggered by the positioning of the case 10. This microswitch operates a solenoid 327 which actuates the magazine shutter mechanism 325. A metal 18 is thus discharged and permitted to drop vertically from the magazine 166 onto the case 10.

Since the case 10 is properly indexed, the metal 18 drops down over the studs 41 and 44 as illustrated in FIG. 2 and FIG. 4 so that the metal is properly and accurately positioned on the assembly. Once the solenoid 327 has been actuated so as to permit the metal 18 to drop onto the case 10, the conveyor 326 commences operation and transports one case having a metal thereon from the metal station 3 to the next station; namely, the rivet station 4. Simultaneously of course, another case is accurately indexed and positioned beneath the magazine 272.

The stations are spaced from each other so that even though the operations performed are intermittent operations, the cases which are indexed beneath one station or in one station will be properly indexed in each succeeding station. That is, when a metal 18 is being indexed in the metal station 3, the case having the metal thereon is also properly positioned and indexed in the fourth or rivet station 4.

D. Rivet Station

Referring to FIG. 28, a conveyor 356 transports the case 10 with the metal 18 thereon into position at the rivet station 4. At the rivet station 4, a pair of rivet driving mechanisms 352 and 354 are positioned over the conveyor 356 to drive a rivet as at 20 in FIG. 4 into the projection as at 44 in FIG. 4. The mechanisms 352 and 354 are a standard type and are commercially available. A typical mechanism is identified by the trade name Riv-A-Matic by the American Rivet Company, Model No. 26, Franklin Park, Illinois. The mechanisms 352 and 354 are appropriately mounted over the conveyor 356 so that when the case 10 is indexed and the conveyor 356 ceases to move, a rivet 20 will be driven into the stud projections 41 and 44.

In combination with the mechanisms 352 and 354 are a number of positioning devices which insure that the mechanisms 352 and 354 will eject a rivet at the appropriate time and only when the metal 18 and case 10 are properly aligned and locked into position on the conveyor 356. Thus, when the conveyor 356 moves the case 10 into position, a micro-switch at 360 operates to position a side anvil mechanism 361 with anvil 316A at the edge of case 10 where the rivet will be driven. This provides a backing for the case 10 when the mechanism 352 discharges a rivet into the stud as at 41. The anvil 361A also cooperates with another anvil (not shown) on the opposite side of the conveyor 356 to lock the metal 18 and case 10 in position.

The micro-switch 360 also activates a hydraulic cylinder 362 that drives a positioning block 363 mounted in bracket 365 downward onto the metal 18. This locks the metal 18 in a tight position against the case 10 and prevents any undesirable movement. The mechanisms 352 and 354 are triggered in their operation when the movement of the block 363 into position against the metal 18 activates a micro-switch mounted on bracket 365.

After the firing of the mechanism 358, the reverse sequence of the operation is effected. Namely, the block 363 retracts. In addition, the anvil 361 is retracted and the case 10 which is now completely finished in its construction is removed from the rivet station 4 by operation of the conveyor 356. The finished binders may then be packed in the manner illustrated by FIG. 29 for shipment.

While the foregoing has set forth a preferred embodiment of the present invention, it is to be understood that all the embodiments which are equivalent thereto are to be included within the scope of the following claims.

What is claimed is:

1. An apparatus for manufacturing binders of the type including a case, at least one spine member, a metal, and fastening means for fastening said spine and metal in cooperative relationship with said binder comprising, in combination:

means for making openings through said case,
means for positioning said spine with said case in a predetermined geometrical relationship with said openings,
means for positioning said metal in cooperation with said spine and said case, and
means for securing said fastening means through said metal in said case and said spine.

2. The apparatus of claim 1 wherein said binder is of the type which includes an inner spine member and an

outer spine member, said metal being contacted with said inner spine member and wherein said means for positioning said spine comprises,

means for positioning said case to receive said spine members,

means for transporting said outer spine member to the outside surface of said case and maintaining said outer spine member against said case,

means for transporting said inner spine member to the inside surface of said case and for maintaining said inner spine member against said case, and

means for fastening said spine members together.

3. The apparatus of claim 1 wherein said means for making openings comprises,

means for aligning said cover,

means for making openings through said case when said case is held in said aligned position, and

means for discharging said case subsequent to providing openings therethrough.

4. The apparatus of claim 1 including means for applying adhesive to said case prior to the attachment of said spine and said metal.

5. The apparatus of claim 1 wherein said means for making openings includes means for aligning a single cover prior to making said openings through said case.

6. The apparatus of claim 1 wherein said means for positioning said spine includes means for wrapping said spine with material prior to positioning said spine relative to said case.

7. The apparatus of claim 1 wherein said means for making openings comprises a platform for said case, cover positioning means for driving said case onto said platform, punch means positioned over said platform to punch said case subsequent to positioning thereof by said case positioning means, control means for operating said means for positioning said punch means, and means for discharging said case subsequent to making openings therethrough by said punch means.

8. The apparatus of claim 7 wherein said case positioning means comprise a drive plate for engaging said case and moving said case to a required position on said platform.

9. The apparatus of claim 7 wherein said platform includes anvil means therein cooperative with one side of said case and hammer means cooperative with the opposite side of said case and said anvil means to secure said case in fixed, desired position subsequent to punching openings therethrough.

10. The apparatus of claim 7 including adhesive dispensing means for placing adhesive on said case prior to attachment of said spine member thereto.

11. The apparatus of claim 7 including magazine means for dispensing cases serially to said punch means.

12. The apparatus of claim 7 including transport means for transporting said cases from said means for making openings in said cases to said means for positioning said spine with said case.

13. Apparatus for providing precisely positioned openings in the case of a loose-leaf binder during the manufacturing operation of said binder comprising, in combination, a platform for receiving said case, a plate for driving said case on said platform, an anvil incorporated as a portion of said platform, a hammer cooperative with said case and said anvil to hold said case in a fixed position on said platform, means associated with said hammer to provide openings through said case and

control means to control the sequence of operation of said platform and said means for providing openings in said case.

14. The apparatus of claim 13 including means for dispensing adhesive onto said case to thereby facilitate cooperation of said case with a spine of a binder during a manufacturing operation.

15. The apparatus of claim 13 including guide means on said platform for assisting in the positioning of said case.

16. The apparatus of claim 1 wherein said means for positioning said spine with said case comprise a separate working section, including means for positioning said case in said station in cooperation with an outer spine member and an inner spine member, one of said spine members including projections for extending through said openings defined in said case and adapted to cooperate with said other spine member.

17. The apparatus of claim 1 wherein said means for positioning said spine with said cover comprises a spine carrying member for carrying a spine to a first position, means for maintaining said spine member in said first position, means for transporting said case over said spine member in said first position, such that said spine member comprises the outer spine member of said binder, means for transporting an inner spine to said first position on the opposite side of said case and means for fastening said spine members together.

18. The apparatus of claim 1 wherein said means for positioning said spine with said case includes a frame, means for storing spines in said frame, means for discharging and positioning a single spine at a work position in said frame, means for subsequently transporting a case to said work position, and means for attaching said spine to said case.

19. The apparatus of claim 1 wherein said means for positioning said spine with said case includes a frame, means for transporting a single spine to a work position in said frame, means for subsequently transporting a case to said work position, and means for attaching said spine to said case.

20. The apparatus of claim 1 wherein said means for positioning said spine with said case includes frame means, a pair of spine transport arms, means in said frame means for operating said transport arms and moving said arms from a first position for receipt of a spine to a second spine discharge position at a work position, means for discharging said spine at said work position, means for subsequently positioning a case at said work position, and means for attaching said spine to said case.

21. The apparatus of claim 20 wherein at least two pairs of spine transport arms are provided to transport said spine members.

22. The apparatus of claim 20 wherein said work position includes a pocket member for receipt of said spine.

23. The apparatus of claim 21 wherein said work position includes means for maintaining said spine member in a relatively fixed immovable position, said means including a pocket member for receipt of said spine.

24. The apparatus of claim 20 wherein said work position includes a pocket member having at least one pivotal end plate, said end plate adapted to pivot and engage a spine member and hold said spine member in said pocket upon release of said spine member to said work position.

25. The apparatus of claim 20 including vacuum port means for positioning a spine on said spine transport arms.

26. The apparatus of claim 20 wherein said means for attaching said spine to said case includes a head assembly, means for transporting said head assembly over said work position subsequent to positioning said case over said spine, said head assembly including means for engaging and fastening said spine to said case.

27. The apparatus of claim 20 including means for positioning a cover over said spines before said spines in said case are attached together.

28. The apparatus of claim 20 including a cover positioning mechanism mounted on said frame, said cover positioning mechanism operative to position a cover at said work position prior to placement of said spine at said work position.

29. The apparatus of claim 28 including means for wrapping said spine with said cover prior to positioning of said case over said spine.

30. The apparatus of claim 20 including means for positioning a cover at said work position prior to placement of said spine, means for wrapping said cover about said spine, means for subsequently positioning said case over said wrapped spine, means for positioning a second spine over said case and said spine, and

means for attaching said spines together in rigid relationship on opposite sides of said case.

31. The apparatus of claim 20 including means for removing the assembled spine and case from said work position and subsequently positioning said assembled spine and case to receive said metal.

32. The apparatus of claim 20 wherein said frame means has motor means mounted thereon, said motor means operative to drive a shaft, said shaft including a plurality of mechanical linkages to drive said spine transport arms, said means for positioning said case and said means for attaching said spine to said case.

33. The apparatus of claim 20 wherein said frame means includes means for providing vacuum suction selectively to said work position during the assembly operation performed by said apparatus.

34. The apparatus of claim 1 wherein said means for securing said fastening means comprises at least one apparatus for dispensing a fastener into fastening cooperation with said binder, said means for dispensing being positioned on a frame and mounted over a conveyor for transporting said case.

35. The apparatus of claim 34 including means for grasping and maintaining said case, spine and metal in a fixed position during attachment of fastening means.
